UNITED STATES PATENT OFFICE.

ISAAC OLIVER, OF BINGHAMTON, NEW YORK.

TEXTILE SPOOL AND BOBBIN.

Application filed March 3, 1928. Serial No. 258,878.

This invention relates to spools and bobbins and aims to provide a simplified and improved construction thereof.

The primary object is to produce spools and bobbins of a superior, non-breakable and durable character adapted to withstand the rough usage to which such articles are subjected in various textile-mill operations.

The invention will be best understood by reference to the accompanying drawings illustrating one embodiment thereof.

In said drawings:

Fig. 1 is an elevational representation of a spool with head and attachment bushing in applicative relation to the upper end of the barrel, said head and a part of the barrel being shown in section;

Fig. 2 is an elevation illustrating a completed spool with the united parts at one end shown in section;

Fig. 3 is an elevation representing one end of a completed spool;

Fig. 4 is an elevational view of the spool barrel;

Fig. 5 is a sectional view of the bushing taken on the line 5—5 of the first figure;

Fig. 6 is a view similar to said first figure illustrating a spool with bushing of modified form adapting it to a special work purpose, the parts being shown in applicative relation to the lower end of the barrel;

Fig. 7 is an elevation of a complete spool having a modified form of bushing at its lower end represented in engagement with a special work element;

Fig. 8 is an enlarged perspective view of said modified form of bushing; and

Fig. 9 is an elevation representing the work-end of the spool shown in Fig. 7.

Referring to the drawings, 10 denotes the barrel or stave of a spool or bobbin. Said barrel is made preferably of wood and is usually trimmed to cylindrical form. In the illustrative embodiment, both ends of the barrel are tenoned or formed with reduced extensions 10^a (see Fig. 4) through which the barrel is axially bored. The ends of the barrel are also formed with narrow recesses 11 of appropriate depth in the plane of and conforming with the peripheries of the reduced extensions coaxially of the barrel bore. Said recesses in effect prolong and space said extensions from the outer walls of the barrel for an appreciable distance within the barrel.

In this instance, the reduced extensions and surrounding recesses in the ends of the barrel

are annular but may advantageously be made polygonal in form.

Heads for the ends of the barrel are shown provided by discs 12 which in this instance are 60 of hard vulcanized-fibre or other composition resisting breakage and rupture. Said heads are cut or punched from slabs of the component material and trimmed to desired form with central apertures 12^a of shape and diameter corresponding with the recesses 11 in the barrel ends. The walls surrounding said apertures may be advantageously threaded or serrated as represented in Fig. 1, or left smooth as shown in Fig. 6. The heads are 70 shown also counter-recessed in one side or face to provide a ledge or shoulder 12^b around their central apertures for a purpose hereinafter appearing.

Means attaching the spool heads to the 75 barrel ends is shown provided by bushings 13 adapted to fit into said ends in engagement with the heads. In the illustrative embodiment, said bushings comprise metallic sleeve-like members having their body-portions threaded or spirally serrated as represented at 13^a and formed with outwardly extended flanges 13^b at one end fitting into the aforesaid counter-recesses in the spool heads. The threads in the body-portions of the bushings are formed preferably on both the inner and outer sides at a pitch sufficient to permit a quick driving thereof into wood (see Fig. 5). In certain instances, it may also be desirable to serrate the under side of the bushing flanges as represented in said figure, while in certain instances it may also be desirable to serrate or corrugate the periphery of said bushing flanges so that the material thereof may impregnate or bite into the material of 95 the heads when driven thereagainst.

In assembling the spool, the heads are placed with their flat sides or faces against the ends of the barrel and with the reduced extensions of the latter projecting through 100 their central apertures. The described bushings are then inserted within said apertures of the heads and applied over said extensions of the barrel at either end by pressure driving them into the recesses 11 with their body-portions threadably engaging in the wood of the barrel on both sides and with their flanges 13^b seated on the ledges 12^b of the heads so as to lie flush with the surfaces thereof. The bushings are thus wedged into place between 105 substantial portions of the wooden barrel with their flanges over-engaging and press-

ing against the outer faces of the heads so as firmly to attach them to the barrel.

So firmly are the heads thus secured to the barrel that it is almost impossible to remove them without breaking the barrel or cracking the heads by undue force. Moreover the heads cannot move or slip in relation to the barrel because of their tight and positive engagement therewith, especially if the undersides or peripheries of the bushing flanges are serrated to impress in the material of the heads as hereinbefore suggested. This will be true whether or not the aperture walls of the heads are threaded as represented in Fig. 1, or left smooth as shown in Fig. 6. Still greater assurance against such slippage would result from making the recesses 11, the apertures of the heads and said bushings in polygonal shape. In some instances it may also be desirable to glue-coat the bushings before driving them into the barrel ends, thus further assuring a firm unity between the parts.

A simplified and improved spool or bobbin is accordingly produced which not only is non-breakable under normal conditions of rough usage in textile-mills, but is also virtually impervious to moisture and will therefore last indefinitely. Its advantages over spools of less sturdy construction in prior art developments will be quickly recognized from the economic standpoint both in manufacture and use.

Upon simple modification, the head-attaching bushings 13 may advantageously be made to serve a special work purpose adapting the spools to use as "twisters". An embodiment thereof is illustrated in Figs. 6 to 9 wherein the modified form of bushing is shown applied to one end of a spool of construction otherwise the same as hereinbefore described, except that the reduced extension of the barrel at that end is of somewhat greater length.

In the illustrative modified construction, the bushing 13 for the lower or work-end of the spool is shown formed with a cap-like portion 13^c in prolongation of its body-portion on the opposite side of the flange 13^b. In said cap-like portion, a central aperture 13^d and a diametrical slot 13^e are formed to provide for connection with a driving element.

The bushing thus formed is driven into the end of the spool barrel for attaching a head thereto in the manner already described. In this instance the cap-like portion of said bushing engages over the reduced extension of the barrel which is correspondingly slotted and provides a ferrule-like shield therefor. Accordingly, said bushing serves a dual purpose and may be characterized as a combined head-attaching means and "twister-shield" for the spool.

65 A spool with end bushing of the modified

form is obviously adaptable to connection with rotary driving means such as a twister-spindle 14 represented in Fig. 7. In said figure, such a spool is shown slipped over the extended shank 14^a of the spindle with the slot 13^e of its bushing engaging over radial driving lugs 14^b of the latter in a well known manner.

The utility and advantage of the modified form of bushing combined with its value as an improved means of securing heads to a spool barrel will be readily appreciated.

Having thus described my invention, what I claim as new and desire to secure by Letters Patent of the United States is:

1. A spool or bobbin comprising a wooden barrel having reduced coaxial extensions and recesses in its ends elongating said extensions, disc-like heads faced against the ends of the barrel and having central apertures into which said barrel extensions project, and bushings driven through said apertures of the heads over said extensions of the barrel and into said recesses at either end thereof, said bushings having threaded body-portions engaging in the wood of the barrel and outwardly extended flanges seated upon the heads thereby holding the same secure to the barrel.

2. A spool or bobbin comprising a wooden barrel having reduced coaxial extensions and recesses in its ends elongating said extensions, disc-like heads faced against the barrel ends and having central apertures into which said extensions of the barrel project, and bushings having threaded body-portions and outwardly extended flanges securing the heads to the ends of the barrel, said bushings being driven through the apertures of the heads over said extensions of the barrel into the recesses at either end thereof with their threaded portions engaging in the wood of the barrel and their flanges seated upon the heads around the edge of the apertures therein.

3. A spool or bobbin comprising a wooden barrel having reduced coaxial extensions and recesses in its ends elongating said extensions, disc-like heads faced against the barrel ends having central apertures of diameter and shape corresponding with the recesses in the barrel and into which said extensions of the barrel project, and bushings having threaded body-portions and outwardly extended flanges securing the heads to the barrel ends, said bushings being of shape corresponding to said recesses in the barrel and driven through the apertures of the heads over said extensions of the barrel into the recesses at either end thereof with their threaded portions engaging in the wood of the barrel and their flanges engaging over the heads around the edge of the apertures therein.

4. A spool or bobbin comprising a wooden barrel having reduced coaxial extensions and recesses in its ends elongating said exten-

sions, disc-like heads faced against the barrel ends and having central apertures into which said extensions of the barrel project, and bushings driven through the apertures of 5 the heads over said extensions of the barrel and into the recesses in the ends thereof for securing the heads to the barrel, said bushings having body-portions threadably engaging in the wood of the barrel and outwardly extended flanges seated upon the heads around the edge of the apertures therein, together with slotted cap-like portions ferruling the extensions of the barrel.

5. In a spool or bobbin embodying a 15 wooden barrel having reduced coaxial extensions and recesses in its ends elongating said

extensions, means for securing an apertured head to an end of the barrel comprising a metallic sleeve-like bushing having threaded body and slotted cap portions together with 20 an intermediate outwardly extended flange, said bushing being driven with its threaded body-portion extending through the apertured head over the reduced extension of the barrel and into the recess therein in wedging 25 engagement with the wood of the barrel and with its flange seated upon the head around the edge of its aperture, its cap-portion being thereby engaged over the reduced extension of the barrel to ferrule the latter.

In testimony whereof I affix my signature.
ISAAC OLIVER.
